UNITED STATES PATENT OFFICE.

CHARLES GROLL, OF ROUBAIX, FRANCE.

SELF-FEEDING SMOKE-CONSUMING FURNACE.

SPECIFICATION forming part of Letters Patent No. 578,146, dated March 2, 1897.
Application filed October 21, 1896. Serial No. 609,499. (No model.) Patented in France May 30, 1896, No. 266,699.

To all whom it may concern:
Be it known that I, CHARLES GROLL, engineer, of Roubaix, Department du Nord, in the Republic of France, have invented a new and Improved Rotatory Grate and Self-Feeding Smoke-Consuming Furnace, (for which I have obtained Letters Patent of France for fifteen years, dated May 30, 1896, No. 256,699;) and I do hereby declare that the following is

10 full and exact description thereof, reference is being made to the accompanying drawings.
In all rectangular or round grate-furnaces, the gases evolved are carried away behind the bridge-wall before having been consumed, and consequently the yield of heat given by the fuel has been heretofore small when compared with that which might in theory be produced.

20 A great many devices have been proposed to do away with smoke, which is injurious both from an economic and a hygienic point of view; but in general the utility of such devices depends on proper care on the part of such stoker, since, notwithstanding the charges of the additions made, some of which are fixed grates or others movable in their constitutive parts, but all belong to one or other system, the general economy of which has remained the same as

30 in the past.
My invention has for its object to get all the smoke consumed by rendering the combustion methodical—that is to say, first, by getting the fresh coal always to come onto the coal which is incandescent; secondly, by increasing the length of the course followed by the gases produced in the combustion-chamber and, by keeping them there as much as possible, and, thirdly, by conducting the said

40 gases successively from the relatively coolest to the hottest portion of the fuel.

In order to insure the desired result, my invention consists, essentially, in the hereinabove particular arrangement of a rotatory grate in combination with a coal-feeder.

50 automatically, in the hereinabove particular arrangement of a rotatory grate in combination with a coal-feeder.

Certain details and construction of the

60 apparatus are shown in Figs. 9

The accompanying drawings clearly show and which I desire to secure by Letters Patent section of a steam-generating furnace on the broken line 1 2 3 4 of the section being made, the greater part of the furnace being on the line 7 8 of Fig. 1. Fig. 4 is a plan of the bars of the furnace. Fig. 3 is the longitudinal axis of the furnace. Fig. 2 is a plan of the bars being moved, the section on the line 5 6 of Fig. 1. Figs. 5 and 6 are detail of the furnace being made in the longitudinal axis of the furnace. Fig. 5 is a plan of the bars of the furnace. Fig. 6 is detail of the furnace being moved, the section on the line 9 10 of Fig. 1. Figs. 7 and 8 are detail of the furnace being moved, the section on the line 9 10 of Fig. 1. Fig. 7 shows the feeder cylinder and Fig. 8 is a cross-section. Fig. 9 is a cross-section of the grate. Figs. 10, and 11 are the supporting arms of the grate. Fig. 12 shows a modification to be applied to a generating form.

The grate-support comprising six rollers b are mounted in support c of the ash-pit. They are not to offer any resistance to the contraction of the grate, which is provided in two parts to move longitudinally into position.

Six radial arms are provided at their said ends. Six radial lugs C are provided at the spaces between the hub C and the spaces between the radial lugs C. The radial lugs C are of the same length to provide a variable width of the grate. Figs. 9

where A is the coal-chamber, B the furnace, C the boiler, D the chimney, E the smokestack, F the smokebox, G the firebox, H the furnace door, I the smokebox door, J the smokebox door, K the smokebox door, L the smokebox door, M the smokebox door, N the smokebox door, O the smokebox door, P the smokebox door, Q the smokebox door, R the smokebox door, S the smokebox door, T the smokebox door, U the smokebox door, V the smokebox door, W the smokebox door, X the smokebox door, Y the smokebox door, Z the smokebox door.

During very sim-
ilarly to one
in the winter f. - 130
which usually
comes

sumption of the smoke, because they are more and more completely come into contact with coal which is more and more incandescent, all moving in the same direction.

My invention of a rotative granular coal-feeder is applicable to the usual constructions of generating

I reserve to myself the right to 10 at will the lower diameter of the order to transform the ordinary furnace into a furnace having instead of a ring in which the rotative generate, and to which may be adapted 15 a granular coal-feeding device, so as to smoke-consuming furnace similar to that hereinbefore described, with the consequence, that the central portion would be omitted entirely, as will be 20 from the cross-section represented.

Having now ascertained the nature of my said invention and in what manner it is to be performed, I declare that my claim is—

25 1. A furnace, provided with a grate, arranged in the combustion-chamber or ceiling forming a passage 1 leading forwardly from one half of the grate, and a vault forming a passage leading 30 to the other half of the grate, and a channel connecting the rear portion of the passages, the forwardly-leading passage being connected to the chimney at substantially as described.

35 2. A furnace, provided with a grate, arranged in the combustion-chamber or ceiling forming a passage 1 leading forwardly from one half of the grate, and a vault forming a passage leading 40 to the other half of the grate, a vertical channel connecting the rear ends of said vault, and a channel connecting said passage to the vertical wall, the forwardly-leading passage being connected to the chimney at substantially as described.

45 3. In a smoke-consuming furnace, mounted to turn, a coal - feed apparatus, a grate, a radial chamber, placed around the coal-feeder and connected, at 50 the grate, with the standard around which said grate revolves, in order that, on the hand, the fresh air coming from the said chamber may become heated, and, on the other hand, moving toward the central standard, then be driven out by the help of the air-jets issuing from on
